(57) **CLAIM**

The ornamental design for a clip, as shown and described.

DESCRIPTION

FIG. 1 is a perspective view of a clip showing a first embodiment of our new design;

FIG. 2 is a plan view thereof, the side opposite that shown in FIG. 2 being the mirror image thereof;

FIG. 3 is a cross-sectional elevation view on the line 3—3 of FIG. 2;

FIG. 4 is a perspective view of a second embodiment of a clip showing our new design;

FIG. 5 is a plan view of the second embodiment, the side opposite that shown in FIG. 5 being the mirror image thereof;

FIG. 6 is a cross-sectional elevation view taken on the line 6—6 of FIG. 5.

FIG. 7 is an edge elevation from the bottom of each of FIGS. 2 and 5, the side opposite that shown in FIG. 7 being the mirror image thereof; and,

FIG. 8 is an end elevation view from the right of each of FIGS. 2 and 5, the side opposite that shown in FIG. 8 being the mirror image thereof.
